WILLIAM E. HASKELL, OF BRATTLEBORO, VERMONT, ASSIGNOR TO ESTEY ORGAN COMPANY, OF BRATTLEBORO, VERMONT, A CORPORATION OF VERMONT.

SWELL-REGULATING MECHANISM FOR ORGANS.

1,281,564.

Specification of Letters Patent. Patented Oct. 15, 1918.

Application filed February 7, 1917. Serial No. 147,082.

To all whom it may concern:

Be it known that I, WILLIAM E. HASKELL, of Brattleboro, in the county of Windham and State of Vermont, have invented a new and Improved Swell-Regulating Mechanism for Organs, of which the following is a specification.

The object of the present invention is to automatically control the swell shades of an organ which is played from a perforated note sheet. In accordance with the present invention the tracker over which the note sheet travels is provided with holes additional to those employed for governing the sounding devices of the organ, these special holes coöperating with special apertures in the note sheet. These special holes through regulating mechanism control the opening and closing of the shutters or "shades" of the swell box or boxes.

The invention is illustrated in the accompanying drawings, in which—

Figure 1, is a cross section of a tracker box illustrating the tracker, the music and take up rolls and the note sheet. Fig. 2, is a cross section of a tube bar illustrating an electric switch which is pneumatically controlled from the tracker. Fig. 3, is a front view of one end of the tracker illustrating the extra holes which are employed for controlling the shade-regulating mechanism. Fig. 4, is a plan view, partly in section, of the shade regulating mechanism. Fig. 5, is a side view partly in section of the shade regulating mechanism. Fig. 6, is an end view of the shade regulating mechanism. Fig. 7, is a vertical cross section of the shade regulating mechanism in the plane indicated by the line 7—7 in Fig. 5. Fig. 8, is a horizontal section illustrating the shade actuating mechanism. Fig. 9, is a vertical section in the plane indicated by the line 9—9 in Fig. 8.

The swell shades are automatically governed from a selector consisting of a traveling apertured note sheet A, (Fig. 1) co-operating in the usual manner with a tracker B, having two rows of holes. During automatic playing the box C, inclosing the tracker is air tight, and contains air under pressure. The tracker near one end has two special holes a and b (Fig. 3), by means of which the shades are controlled. Each of these holes communicates by a tube

c, with a channel d (Fig. 2), in a tube bar D. 55 Each channel d, communicates with the interior of a primary pneumatic E, consisting of a sliding metal cup. When an aperture in the note sheet registers with one of the special holes, say a, in the tracker, air flows 60 through pipe c, and channel d, into the pneumatic E, which lifts, and closes an electric switch controlled by the pneumatic and a fixed spring terminal e, which through bus-bar f, is connected with one pole of an 65 electric generator. The pneumatic E, is permanently connected by coiled wire g, and conductor h, with wire i. This wire leads to the shade-regulating mechanism and thence to the opposite pole of the generator. 70 When the circuit is closed by the lifting of the pneumatic E, certain of the shades are closed as determined by the regulating mechanism.

Likewise, when the other hole b, is uncovered, a similar primary pneumatic E, (on the same tube bar D, or on a different tube bar,) is lifted and a second circuit is closed leading to the regulating mechanism, and certain of the shades are opened as determined by the regulating mechanism.

In practice, the swell actuating mechanism has been applied to an organ in which the pipes belonging to the swell organ have been inclosed in one chamber or box and the pipes belonging to the great organ have been inclosed in a second chamber or box. Each of these boxes is equipped with shutters or "shades" and by the opening and closing of the shades or a portion of them the volume 85 of sound from both departments is regulated. In the case of the specific organ illustrated, each chamber has seven shades and the regulating mechanism is constructed to automatically open and close variably the 90 seven shades of each chamber. All of the shades are alike and actuated in the same manner. Accordingly, in Fig. 8, the actuating mechanism for a single shade F, only, is illustrated. As shown in Fig. 8, the shade F, is pivoted so as to swing on a vertical axis l, and it has a crank arm m. This crank arm is connected by a link G, and connecting rod U, to the outer end of a lever H, pivoted at n, to a stationary board. 105 The lever H, is acted upon by a spring I, which normally (that is when the organ is not in use) maintains the lever H, rod U,

link G, and shade F, in the position illustrated by full lines in Fig. 8; hence normally maintaining the shade F, opened. The lever H, is connected by a link J, to the movable board of a pneumatic motor K, which is normally maintained collapsed by the spring I. As shown in Fig. 9, the interior of the bellows communicates by a pipe L, and passage M, through a port o, with a supply box N, containing air under pressure and through a port p, with the atmosphere. The ports o and p, are controlled by connected valves O and P, which are connected with the movable board of a pneumatic Q. 15 Normally the pneumatic Q, is collapsed and the valve O, closes the port o, whereas the valve P, is open so that the motor K, is vented through the port p, to the open air. The interior of the pneumatic Q, communicates by a passage q, with a channel r, which is normally vented to the open air through a vent s. This channel r, communicates through a passage t, with a chamber R, containing air under pressure. The vent s, and passage t, are controlled by a valve S, which is in turn governed by an electro-magnet T, of the solenoid type. Normally the valve S, closes the passage t, leaving the vent s, open. In case, however, that the magnet T, is energized by the closing of the electric circuit which includes it, the valve S, is lifted thereby closing the vent s, and establishing communication between the interior of the pneumatic Q, and the pressure chamber R, through passage q, channel r, and passage t. The result is that the pneumatic Q, is expanded so that the valve P, closes vent p, and valve O, is opened so that compressed air flows from supply box N, through port o, passage M, and pipe L, to the interior of the motor K, which thereupon expands. The expansion of the motor K, moves the lever H, and the link G, to the positions shown in dotted lines in Fig. 8, thereby 45 closing the shade F, as indicated by dotted lines in Fig. 8. The shade F, remains closed so long as electric current flows through the electro-magnet T. When the current is cut off, the valve S, drops thereby closing the passage t, and venting channel r, to the open air through vent s. Consequently, the pneumatic Q, collapses by gravity, valve O, closes and valve P, opens. The pneumatic K, is thus vented to the open air, and the spring I, collapses the motor K, and the shade F, is opened. There is a similar electro-magnet T, valve S, motor K, and spring I, for each shade F, so that the illustration of one set of shade actuating mechanisms suffices for 55 all.

In practice the actuating mechanism for the shades is arranged in two groups, one for each of the pipe-containing chambers of the organ. Also, the several pneumatic motors K, and the connections therewith employed

for the shades of each chamber are arranged at successively different heights so as not to interfere with each other. Fig. 9, for example, indicates a pipe L¹, extending upwardly so as to supply air to a motor K, higher up 70 than the one illustrated; this pipe L¹, being similar in function to the pipe L.

The shade regulating mechanism is shown in Figs. 4, 5, 6 and 7. From the controlling magnet T, of each shade, a wire 1, leads to a 75 spring terminal 2 (Fig. 4.). There are as many of these terminals as there are shades, fourteen being shown in Fig. 4. As there shown, they are arranged in three groups X, Y, and Z, there being eight in group X, 80 four in group Y, and two in group Z.

Alternate terminals 2, belong to the two pipe chambers. Hence four terminals of group X, two terminals of group Y, and one terminal of group Z, belong to the 85 shades of each pipe chamber. Only a single wire 1, is illustrated in Fig. 4, so as to avoid confusion. There is a separate wire 1, for each terminal 2, and each wire 1, leads to the electro-magnet T, of the correspondence 90 shade.

All of these terminals are adapted to co-operate with a single movable regulator 3. This regulator when the organ is in use is in permanent electrical connection with 95 one pole of a generator by means of spring contact 4, and wire 5. As shown in the drawings, the regulator 3, is a sliding metal plate, which can be moved so as to contact with none of the terminals 2, or 100 successively with the several groups X, Y, and Z. As shown in Fig. 4, the regulator is in contact with none of the terminals 2, and hence all of the shades are open. This is desirable because when the organ is idle 105 the pipe chambers are ventilated through the open shades.

The regulator 3, has a group of three shoulders 6, 7 and 8, which co-operate with an advancing actuator 9 (Figs. 4, 5 and 6); 110 and a second group of three shoulders 10, 11, and 12, which co-operate with a retracting actuator 18.

The wire i, from the primary pneumatic E, controlled by the tracker hole a, leads 115 to an electro-magnet 14, of the solenoid type, and when that pneumatic is lifted a valve 15 (Fig. 6), connected with the core of magnet 14, is lifted. When the valve 15, is lifted, air passes from an air chamber 16 120 (Fig. 6), containing air under pressure, through tube 17, and passages 18 and 19, to a pneumatic 20, which thereupon expands. The advancing actuator 9, is connected to the movable board of the pneumatic 20, and, hence, when that pneumatic 125 expands, the actuator is lowered until it comes in contact with the regulator 3, just back of (to the right of, as in Fig. 5) the shoulder 6. The actuator 9, is of metal; 130

and, when it touches the live regulator 3, the electric current flows through spring 21 (connected with the actuator), rod 22, and wire 23, to the electro-magnet 24, and the valve 25 (Fig. 7), thereof then lifts. Thereupon, air flows from chamber 16, through tube 26, and passages 27 and 28, to the interior of bellows 29 (Fig. 5) which expands. This bellows 29 constitutes the advancing motor. A link 30, is connected to the movable board of the advancing motor 29, and also to the actuator 9, which passes loosely through a hole in the outer end of the link as shown in Fig. 5. Hence, the lower end 10 of the actuator is moved forwardly (to the left, Fig. 5) carrying with it through shoulder 6, the regulator 3. The stroke of the advancing motor 29, is just sufficient to move the regulator forwardly enough to contact 15 with all of the terminals 2, of group X, thus completing circuits therethrough, and closing the corresponding shades, four in the swell chamber for the swell organ, and four in the swell chamber for the great organ. 20

When the travel of the note sheet covers the tracker hole *a*, the corresponding channel *d*, in the tube bar D (Fig. 2), is vented at the bleed *j*, and primary pneumatic E, drops thus breaking the circuit which includes the magnet 14. Thereupon, the valve 15, drops thus venting the passage 19 and the pneumatic 20, collapsing the pneumatic; and the spring 21 (Fig. 5), lifts the actuator 9, above the regulator 3, and its shoulders 6, 7 and 8. This breaks the circuit through the magnet 24, and its valve 25 drops thus venting passage 28 and motor 29, which then collapses under the influence of spring 31 (Fig. 5). This swings the lower end of the actuator 9, to the right (Fig. 5); and, since the regulator is left in its first advanced position contacting with the terminals of group X, the lower end of the actuator 9, is now above the space 35 between the shoulders 7 and 8.

The effect of this forward step of the regulator is to connect all of the terminals of group X, with the electric generator and hence to close four shades in each of the two pipe inclosing chambers of the organ. In case the musical composition next demands still softer playing a second aperture in the note sheet uncovers the same hole *a*, in the tracker with the result that the actuator 9, is again depressed into contact with the regulator, and is moved again to the left, this time acting upon shoulder 7, and thus moving the regulator a further step forward thereby bringing it into contact with 40 the terminals 2, of the second group Y. The result is to close two additional shades in each of the two pipe inclosing chambers with the result that a still less volume of sound is produced. In case the musical composition then requires the softest playing

another aperture in the note sheet for the third time uncovers the hole *a*, in the tracker; and, consequently, the actuator 9, is again lowered into contact with the regulator and, as it this time is behind the third shoulder *s*, on this third movement of the actuator 9, to the left the regulator is moved forward another step thus coming into contact with the terminals of group Z, and hence closing the remaining shades. 45

In case the musical composition requires louder playing and hence the opening of the shades, the regulator is moved backwardly, that is to say, toward the right as shown in Figs. 4 and 5. This backward movement of the regulator is effected through the uncovering of the hole *b* (Fig. 3), in the tracker by means of a registering aperture in the note sheet. This results in pneumatically closing a circuit by a second primary pneumatic E, and its coöperating spring contact *e*, this circuit including a wire *k* (Fig. 5), which leads to another electro-magnet 32, of the shade-regulating mechanism. Thereupon the valve controlled by this magnet is 50 lifted and a pneumatic 34, is thereby put in communication through pipe 33, with the air chamber 16, so that the pneumatic 34, is expanded, and the actuator 13, connected therewith is lowered into contact with the regulator 3. This actuator 13, being likewise an electric conductor, an electric circuit is closed which includes the spring 35, the fixed rod 36, the wire 37, and the electro-magnet 38. This magnet 38, being thus energized, a valve connected therewith is lifted, and air then flows from the air chamber 16, through pipe 39, and passage 40, to the interior of the bellows 41 constituting the retracting motor. The motor 41, then expands 55 thereby moving the connected link 42, to the right. This link 42, is connected with the actuator 13, in just the same way as the link 30, is connected with the actuator 9. Consequently the actuator 13, is moved one step 60 to the right. During this movement the actuator 13, will encounter one of the shoulders 10, or 11, or 12, depending upon the number of steps which the regulator had been advanced under the action of the actuator 9. For example, if the actuator 9, had acted but once through coöperation with shoulder 6, then the shoulder 10, would have been positioned to bring it within the action 65 of the retracting actuator 13. Said actuator 13, acting upon shoulder 10, moves the regulator 3, backwardly (to the right) one step and to just the same extent that the advancing actuator 9, had previously moved the regulator to the left. Likewise, if the actuator 9, had moved twice, the shoulder 11, would have been brought into coöperative relation with the retracting actuator 13; and if the advancing actuator 9, had been removed three times the shoulder 12, would 70

have been brought into coöperative relation with the retracting actuator 13. The retracting actuator 13, undoes the work of the advancing actuator 9. Assuming that the 5 regulator is at its extreme forward position contacting with all of the terminals 2, then the first movement of the retracting actuator 13, would move the regulator one step to the right, and hence cut out the group Z, of terminals, thereby opening the corresponding shades. Then, if the musical composition demanded still louder playing, a second hole in the note sheet would register with the tracker hole b, and the retracting actuator 10 13, would move the regulator another step backward. This would cut out the group Y, of terminals and the result would be to open the shades coöperating therewith. Finally, if the musical composition demanded the 15 loudest playing the actuator 13, would again be brought into play by another aperture in the note sheet again uncovering the tracker hole b, with the result that the selector 3, would be moved backwardly to its extreme 20 extent, thereby cutting out the group X, of terminals with the result that the remaining shades would be opened.

If it is important to pass rapidly from the 25 position where the shades are all open to the position where they are all closed, apertures in the note sheet are placed close together so as to open the tracker hole a, in rapid succession until the regulator has been moved its entire extent. Similarly, if the musical 30 composition requires that there should be an immediate passage from the softest to the loudest playing, a succession of apertures in the note sheet arranged close together coöperate with the tracker hole b, so as to give 35 40 retracting movements to the regulator in rapid succession.

By appropriate location of the apertures in the note sheet registering with the holes a and b, in the tracker, the shades are controlled in any desired order for the desired 45 interpretation of the musical composition which is played under the control of the note sheet.

More than three groups of the terminals 50 2, may be provided with a corresponding increase in the shoulders on the regulator and of the step-by-step movement of the regulator, thereby increasing the variations in the volume of sound. The four variations supplied by the illustrated construction are ample, however, for the general run of musical compositions. Whatever the number of 55 variations may be, two holes in the tracker suffice to effect them.

All four of the electro-magnets 14, 24, 60 32 and 38, are connected with a common bus bar 43, which is connected by wire 44, with one pole of the electric generator. The regulator 3, has a longitudinal slot 45, 65 through which passes a fixed stud 46 (Figs.

4 and 7), which limits the forward and backward movements of the regulator. The regulator is guided at its longitudinal side edges by fixed guides 47 (Fig. 7).

The retracting motor 41, is collapsed by 70 the same spring 31, which collapses the advancing motor 29. The extent of expansion of each bellows is determined by an adjustable padded stop 48 (Fig. 5), so that each actuator 9 or 13, is moved to the correct extent required to move the regulator a single step. Each stop 48, is adjustably mounted on a cross bar 49, supported at opposite ends by the two guides 47, and extending over the regulator. 75 80

I claim—

1. A note-sheet-played organ having shades F; a pneumatic motor K connected with each shade, a spring I acting on each motor to collapse it and open the corresponding shade, an air supply box N communicating with each motor, a valve O controlling the supply of air to each motor, a pneumatic Q for operating each valve, a valve S governing the supply of air to said 90 pneumatic, and an electro-magnet T governing the movement of said valve, in combination with a plurality of terminals 2 each in communication with one of said magnets, 95 said terminals being arranged in groups, a movable regulator 3 adapted to coöperate with said groups of terminals successively but normally out of coöperation with all of them, two groups of spaced shoulders 6, 7, 100 8 and 10, 11, 12 on said regulator, an actuator for each group of shoulders, a pneumatic connected with each actuator and acting when expanded to bring said actuator into contact with said regulator alongside 105 one of said shoulders, a bellows connected with each actuator and acting when expanded to move its actuator so as to move said regulator one step, the two bellows moving in opposite directions so as to move said 110 regulator either forward or back depending upon which actuator is active, an air chamber 16 which supplies air to said pneumatics and bellows, an electrically actuated valve for each pneumatic and bellows governing 115 the supply of air from the chamber thereto, an electro-magnet controlling each valve, and circuit connections between the magnet for each bellows and the corresponding actuator, the circuit therethrough being closed 120 by the actuator coming into contact with the regulator; a tracker having two special holes, an electrical switch coöperating with each hole, a pneumatic controlling each switch, a pipe leading from each of said 125 tracker holes to one of said pneumatics, and a circuit connection from each switch to one of the magnets which governs the pneumatic which acts to bring the corresponding actuator into contact with the regulator. 130

2. A note sheet played organ having shades, and electrically controlled devices for moving each of them, in combination with shade regulating mechanism comprising electric terminals one for each shade in communication with the respective electric controlling devices therefor, said terminals being arranged in groups, a movable regulator adapted to cooperate with said groups of terminals successively but normally out of cooperation with all of them, two groups of spaced shoulders on said regulator, an actuator for each group of shoulders, a pneumatic connected with each actuator and acting when expanded to bring said actuator into contact with said regulator alongside one of said shoulders, a bellows connected with each actuator and acting when expanded to move its actuator so as to move said regulator one step, the two bellows moving in opposite directions so as to move said regulator either forward or back depending upon which actuator is active, an air chamber which supplies air to said pneumatics and bellows, an electrically actuated valve for each pneumatic and bellows governing the supply of air from the chamber thereto, an electro-magnet controlling each valve, circuit connections between the magnet for each bellows and the corresponding actuator, the circuit therethrough being closed by the actuator coming into contact with the regulator; and a tracker having two special holes, an electric switch coöperating with each hole and an electrical circuit closed by each switch and including one of the magnets which governs the pneumatic which acts to bring the corresponding actuator into contact with the regulator.
3. A note sheet played organ having shades, and electrically controlled devices for moving each of them, in combination with shade regulating mechanism comprising electric terminals one for each shade in communication with the respective electric controlling devices therefor, said terminals being arranged in groups, a movable regulator adapted to cooperate with said groups of terminals successively but normally out of cooperation with all of them, two groups of spaced shoulders on said regulator, an actuator for each group of shoulders, a pneumatic connected with each actuator and acting when expanded to bring said actuator into contact with said regulator alongside one of said shoulders, a bellows connected with each actuator and acting when expanded to move its actuator so as to move said regulator one step, the two bellows moving in opposite directions so as to move said regulator either forward or back depending upon which actuator is active, a chamber which supplies air to said pneumatics and bellows, an electrically actuated valve for each pneumatic and bellows governing the supply of air from the chamber thereto, an electro-magnet controlling each valve, and circuit connections between the magnet for each bellows and the corresponding actuator, the circuit therethrough being closed by the actuator coming into contact with the regulator; a tracker having two special holes, an electric switch coöperating with each hole, and a circuit connection from each switch to one of the magnets which governs the pneumatic which acts to bring the corresponding actuator into contact with the regulator.
4. A note sheet played organ having shades, and electrically controlled devices for moving each of them, in combination with shade regulating mechanism comprising electric terminals one for each shade in communication with the respective electric controlling devices therefor, said terminals being arranged in groups, a movable regulator adapted to cooperate with said groups of terminals successively but normally out of cooperation with all of them, two oppositely moving actuators acting to move said regulator step by step in opposite directions, a pneumatic connected with each actuator and acting when expanded to bring said actuator into contact with said regulator, a bellows connected with each actuator and acting when expanded to move its actuator so as to move said regulator one step, the two bellows moving in opposite directions so as to move said regulator either forward or back depending upon which actuator is active, a chamber which supplies air to said pneumatics and bellows, an electrically actuated valve for each pneumatic and bellows governing the supply of air from the chamber thereto, an electro-magnet controlling each valve, circuit connections between the magnet for each bellows and the corresponding actuator, the circuit therethrough being closed by the actuator coming into contact with the regulator; a tracker having two special holes, an electric switch coöperating with each hole, and an electrical circuit closed by each switch and including one of the magnets which governs the pneumatic which acts to bring the corresponding actuator into contact with the regulator.
5. A note sheet played organ having shades, and electrically controlled devices for moving each of them, in combination with shade regulating mechanism comprising electric terminals one for each shade in communication with the respective electric controlling devices therefor, said terminals being arranged in groups, a movable regulator adapted to cooperate with said groups of terminals successively, and two oppositely moving actuators acting to move said regulator.

- 6 lator step by step in opposite directions, independent electrically controlled means governing each actuator; a tracker having two special holes; an electric switch coöperating 5 with each hole, and an electrical circuit closed by each switch and including the controlling means for the corresponding actuator.
6. An automatically played organ having 10 shades, and electrically controlled devices for moving them, in combination with shade-regulating mechanism comprising electric terminals for the shades in communication with the electrical devices controlling 15 the shades, said terminals being arranged in different groups, a movable regulator adapted to coöperate with said groups of terminals successively, and actuating means for moving the regulator step by step in opposite directions, and automatically controlled 20 means for moving said actuating means in opposite directions.
7. An automatically played organ having 25 shades, and electrically controlled devices for moving them, in combination with shade regulating mechanism comprising electrical terminals for the shades in communication with the electrical devices controlling the shades, said terminals being arranged in 30 groups, a movable regulator adapted to co-operate with said groups of terminals successively, two oppositely moving actuators acting to move the regulator step by step in opposite directions, a pneumatic connected 35 with each actuator and acting when expanded to bring said actuator into contact with said regulator, a bellows connected with each actuator and acting when expanded to move its actuator so as to move said regulator 40 one step, the two bellows moving in opposite directions so as to move said regulator either forward or back depending upon which actuator is active, a chamber which supplies air to said pneumatics and bellows, 45 an electrically actuated valve for each pneumatic and bellows governing the supply of air from the chamber thereto, an electromagnet controlling each valve, circuit connections between the magnet for each bellows and the corresponding actuator, the cir- 50
- cuit therethrough being closed by the actuator coming into contact with the regulator and a stop limiting the movement of each bellows; and two automatically controlled circuits each of which includes one of the 55 magnets which governs the pneumatic which acts to bring the corresponding actuator into contact with the regulator.
8. An automatically played organ having 60 shades, and means for moving said shades, in combination with automatic shade regulating mechanism comprising a movable regulator adapted to coöperate variably with said shade-moving means, and actuating means for moving the regulator in opposite directions.
9. A note sheet played organ having a 65 tracker with two special holes controlled by the apertured note sheet and a shade regulator, in combination with an advancing 70 motor and a retracting motor coöperating independently with said regulator to move it in opposite directions, and two primary pneumatics, each controlled through one of the special holes in the tracker and coöperating with one of the motors to govern its action, successive movements of each pneumatic through the repetition of apertures in the note sheet registering with the corresponding special hole acting to effect repeatedly the action of the corresponding motor thereby moving the shade regulator step by 75 step in one direction.
10. An automatically played organ having 80 selectors and a shade regulator, certain 85 of said selectors controlling said regulator, in combination with an advancing motor and a retracting motor coöperating independently with said regulator to move it in opposite directions, each motor being rendered active through one of the shade regulator controlling selectors, successive actions 90 of each of such selectors serving to effect repeatedly the action of the corresponding motor thereby moving the shade regulator 95 step by step in one direction.

In witness whereof, I have hereunto signed my name.

WILLIAM E. HASKELL.
